UNITED STATES PATENT OFFICE.

EDWARD CHARLES FREDERICK OAKLEY, OF NORBURY, ENGLAND, ASSIGNOR OF ONE-HALF TO ARTHUR COLLIER, OF LONDON, ENGLAND.

HACK AND LIKE FRAME SAW.

Application filed March 6, 1925. Serial No. 13,590.

To all whom it may concern:

Be it known that I, EDWARD CHARLES FREDERICK OAKLEY, a subject of the King of Great Britain and Ireland, residing at 5 Norbury, in the county of Surrey, England, have invented certain new and useful Improvements in Hack and like Frame Saws, of which the following is a specification.

The present invention relates to improvements in hack and like frame saws, and it 10 has for its object a form of frame which will enable large sheets of metal or other material to be cut up in any desired manner.

The frames of hand operated hack saws 15 as at present constructed are so formed that it is impossible to separate from a large sheet of metal, a piece of greater width than the distance between the saw and the back of the frame.

20 I attain the object of this invention by the construction shown in the accompanying drawing in which:—

Figure 1 is a side elevation.

Figure 2 is a plan partly in section on 25 line 2, 2 of Figure 1, and

Figures 3 and 4 are end elevations as viewed in the direction of the arrows 3 and 4 respectively of Figure 1.

The frame comprises a long upper rigid 30 member 1 to one end of which a handle 2 is suitably attached, an element of sheet metal 4 riveted or otherwise secured to said member, a short rigid member 3 riveted or otherwise secured to the element 4 at as 35 great a distance from the member 1 as the depth of said element will allow and approximately beneath the opposite end of the member 1 to that to which the handle 2 is attached, and means by which the saw blade 5 may be secured to and tensioned between 40 the members 1 and 3. A convenient method of mounting the blade 5 is that illustrated in which the blade is secured at one end by a bolt and nut 7 to the member 3 and at 45 its other end is secured by a bolt and nut 8, which passes through a slot 9 formed in the member 1, to an adjusting device which comprises a pair of links 10, the other ends of which are connected to the head of a screw threaded member 11 which passes through a washer plate 12 provided on its outer end with a nut 13. The element 4 which is of triangular shape has a thickness not greater than the thickness of the saw 50 blade to be employed. Although this ele-

ment is preferably made as a solid web it may if desired be made of skeleton form.

The rigid members 1 and 3 may each consist of two strips of metal between which the element 4 is placed and the several parts 60 riveted together. The strips forming the upper rigid members may be bent upwards and backwards, and, with a piece of wood placed between the strips, constitutes the handle 2.

65 It will be understood that if it is desired to cut material of greater thickness than is possible with a frame of the proportions illustrated, an element 4 of greater depth may be employed so as to increase the distance between the members 1 and 3.

70 It is not material that the member 3 be arranged parallel with the member 1; it may within limits be arranged in angular relation thereto. It will be appreciated that as 75 the sheet metal element 4 connecting the two elements 3 and 8 is not thicker than the saw blade it will not only follow said blade into the cut made and so permit of any length or width of sheet being cut but will also act as 80 a guide to the saw blade.

What I claim is:—

1. A hack saw comprising a bar, a handle mounted on one end thereof, a spacing web rigidly mounted on said bar, the thickness 85 of which is not greater than the saw blade, a second bar rigidly mounted on said web, a saw blade mounted between said bars so that it lies in the same plane as the web and in angular relation to the bars, and means for 90 tensioning said blade.

2. In a hack saw the combination with the blade, of a frame comprising two bars of unequal lengths, a sheet metal web the thickness of which is not greater than the 95 saw blade which carries and spaces said bars the position of the shorter of said bars relative to the longer one being towards one end of said longer bar, a handle carried by the longer bar at the end opposite to the end 100 adjacent to the shorter bar, and means for attaching the blade to said frame so that it lies in the same plane as the web.

3. A hack saw comprising two bars of unequal length; a handle mounted on one end 105 of the longer bar; a sheet metal web of triangular shape for supporting and spacing said bars one edge of said web being attached to the longer bar another edge of which lies at approximately right angles to 110

said longer bar and the third edge of which lies at an angle of approximately 40° to said longer bar, the thickness of said web being not greater than the saw blade to be employed; and a saw blade tensioned between said bars so that it lies in juxtaposition to the angular edge of the web and in the same plane.

4. A hack saw frame comprising two bars of unequal length; a handle mounted on one end of and above the longer bar; a triangular web of sheet metal rigidly secured to said bars for spacing and position-

ing them, one edge of said web being attached to the longer bar another edge of said web lying at approximately right angles to said bar and the third edge of said web lying at an angle of approximately 40° to said bar, the thickness of said web being not greater than the saw blade to be employed; and means for securing a saw blade to both bars so that it lies in juxtaposition to the angular edge of the web, and for tensioning said blade.

EDWARD CHARLES FREDERICK OAKLEY.
